UNITED STATES PATENT OFFICE.

ALFRED CHARLES SINCLAIR, OF NEW ORLEANS, LOUISIANA, ASSIGNOR TO SINCLAIR MOTOR CO., INC., OF NEW ORLEANS, LOUISIANA, A CORPORATION OF LOUISIANA.

AIR-COOLED ENGINE.

1,366,707.

Specification of Letters Patent. Patented Jan. 25, 1921.

Application filed August 6, 1919. Serial No. 315,759.

To all whom it may concern:

Be it known that I, ALFRED C. SINCLAIR, a citizen of the United States, residing at New Orleans, in the parish of Orleans 5 and State of Louisiana, have invented a new and useful Air-Cooled Engine, of which the following is a specification.

It is the object of my invention to cool internal combustion engines efficiently by 10 air, and especially by air which is also used for scavenging and internal cooling.

My present invention is especially intended to be used in the type of engines set forth in my co-pending application Ser. No. 15 184,643, filed August 6, 1917; but in its broader aspects it is not limited to that type of engine.

The accompanying drawings illustrate 20 my invention: Figure 1 is a vertical central section through one cylinder and crank-case section of an internal combustion engine embodying my invention; and Fig. 2 is a section on the line 2—2 of Fig. 1.

The engine may have any number of cylinders, of which only one is shown in the 25 drawings. The cylinder is a cast-iron cylinder 10, provided externally save at the points where the various ports and their connections are located with a circumferential series of longitudinal grooves 11. Fitting tightly on this cylinder 10 is a jacket 30 12, preferably of aluminum because of its lightness and ease in machining and also because of its high heat conductivity. The 35 aluminum jacket 12 bears against the cylinder at the points between the grooves 11; but such grooves are air passages through which cooling air travels as hereinafter explained, to cool the cylinder 10. The jacket 40 12 is provided with circumferential flanges 13, for radiating the heat which the jacket receives from the cylinder 11. Thus the cylinder is cooled both by the heat radiation from the flanges 12 and also by the absorption 45 of heat by the air which passes through the grooves 11.

At the top of the cylinder 10 is a valve-seat member 15, which is also surrounded by the jacket 12. This valve-seat member 50 is provided with an intake space 16, which receives the explosive mixture from any suitable source, and with an exhaust space 17, which receives the gas forced out of the

engine cylinder on the up-stroke of the associated piston 18. The gas forced out of the 55 cylinder at this time is almost wholly air, because of the scavenging action which will be explained later; and this air cools the walls of the cylinder 10 effectively from the inside. The exhaust space 17 is connected, 60 by suitable grooves 19 on the inside of the jacket 12, with the upper ends of the grooves 11 in the exterior of the cylinder 10, so that the air which is discharged into the exhaust space 17 is carried down through 65 the grooves 19 and 11. The grooves 11 are separate in the upper and lower parts of the cylinder. The lower ends of those in the upper part lead into a circumferential passageway 20 formed in the jacket 12, which 70 circumferential passageway leads to an exhaust opening 21 at one side of the jacket 12. This exhaust opening 21 is suitably connected to any desired exhaust system. The grooves 11 below the level of the passageway 20 and exhaust opening 21 open to 75 the atmosphere at top and bottom by openings 22 and 23 through the jacket 12. By reason of the heating effect of the cylinder 10 on the air within these lower grooves 11, 80 while the engine is in operation there is a continuous circulation of air through such lower grooves, the air entering through the openings 23, being heated in and passing through the lower grooves 11 and cooling 85 the cylinder in its passage, and escaping through the atmosphere through the opening 22.

The valve-seat member 15 is provided with suitable ports communicating with the 90 intake space 16 and exhaust space 17. With this valve-seat member co-operates an oscillating valve 25, which is provided with ports 26 which by the oscillation of such valve in any suitable manner may be moved into 95 registry with the ports from the intake space 16 during the intake period of the engine, and into registry with the ports leading to the exhaust space 17 during the exhaust period of the engine, and out of registry with both sets of ports during the compression and explosion periods. The cylinder 10 is provided in its side walls with one or more supplemental exhaust ports 27, which communicate with the exhaust opening 21 100 and are uncovered by the piston 18 at the

lower end of the piston stroke, to allow the burned gases from the explosion to escape from the cylinder when such ports are uncovered. The cylinder 10 is also provided, 5 on the opposite side from the supplemental exhaust ports 27, with one or more scavenging air-inlet ports 28, for admitting scavenging air into the cylinder shortly after the supplemental exhaust ports 27 are first 10 uncovered by the piston. The scavenging air thus admitted through the ports 28 sweeps out from the inside of the cylinder the bulk of the burned gases which are in the cylinder at the end of the explosion period, so that such burned gases are replaced 15 by the fresh scavenging air; and when the piston 18 moves upward on its exhaust stroke it is thus practically nothing but this displacing scavenging air which is forced 20 out through the ports 26 and into the exhaust space 17 and therefrom through the grooves 11 between the cylinder 10 and its jacket 12.

The scavenging air supplied through the 25 ports 28 is obtained by crank-case compression, preferably in the manner set forth in my aforesaid co-pending application. A rotating valve 30 is suitably operated to admit air into the crank-case section 31 whenever 30 the piston moves upward, on its compression and exhaust strokes, and to allow such air to pass from the crank-case section 31 to the ports 28 of the cylinder 10, or of an associated cylinder in which the piston is 35 moving correspondingly but at the exactly opposite point from the cycle, when the piston is moving downward on its explosion and intake strokes. This is fully explained in my aforesaid co-pending application. 40 When the piston 18 uncovers the ports 28 at the end of its explosion stroke, the air from the crank-case section 31 as well as the air from the crank-case section of the cylinder which is at the diametrically opposite 45 site point in the cycle is admitted through the valve 30 and such scavenging air ports 28 into the cylinder 10, to sweep out the burned gases through the supplemental exhaust ports 27 and displace such burned 50 gases with fresh air. This fresh air, as stated, cools the cylinder walls 10 from the inside during the exhaust stroke of the piston, and when it is forced out through the ports 26 it passes into the exhaust space 55 17 of the valve-seat member and thence through the grooves 12 in parallel to cool the cylinder walls from the outside.

The valves 25 and 30 are operated in any suitable manner. As shown, the valve 30 is 60 driven by suitable gearing from the crank shaft 32 at half the speed of rotation of the crank shaft, so that it makes one rotation for each engine cycle; the crank shaft 32 is connected to the piston 18 by the usual connecting rod 33. The valve 25 is operated,

as for instance by the mechanism set forth in my aforesaid co-pending application, so that it is stationary during the compression and explosion periods of the engine and then has its ports 26 out of registry with 70 both the intake and exhaust ports of the valve-seat member, and so that it is moved only during the intake and exhaust periods, during which periods it is not under pressure from within the cylinder. 75

I claim as my invention:

1. In an internal combustion engine, a cylinder, a metal jacket fitting on said cylinder, the abutting surface of one of said parts where it fits against the other being provided with longitudinal grooves, and connections to said grooves for causing a circulation of air through them in parallel and through the cylinder in series with the grooves, said jacket being provided with heat-radiating 80 flanges. 85

2. In an internal combustion engine, a cylinder having intake and exhaust ports, and a metal jacket fitting on said cylinder, the abutting surface of one of said parts 90 where it fits against the other being provided with longitudinal grooves, said grooves having openings to the atmosphere at points of different heights and separated from the cylinder exhaust port so that by the heating 95 effect of the cylinder on the air in such grooves there is a natural circulation of air through the grooves. 95

3. In an internal combustion engine, a cylinder, a metal jacket fitting on said cylinder, the abutting surface of one of said parts where it fits against the other being provided with longitudinal grooves, and connections to said grooves for causing a circulation of air through them in parallel and 100 through the cylinder in series with the grooves. 105

4. In an internal combustion engine, a cylinder, a metal jacket fitting on said cylinder, the abutting surface of one of said parts 110 where it fits against the other being provided with grooves, means associated with said cylinder for displacing by scavenging air the burned gases in the cylinder at the end of the explosion period, and a valved port 115 by which said scavenging air when forced out of said cylinder is conducted through said grooves. 115

5. In an internal combustion engine, a cylinder and a piston, said cylinder being 120 provided with a plurality of circumferentially spaced longitudinal passageways in its walls, and means for causing a circulation of air through said passageways in parallel and through the cylinder in series with the 125 grooves. 125

6. In an internal combustion engine, a cylinder and a piston, said cylinder being provided with a plurality of circumferentially spaced longitudinal passageways in its 130

walls, and means for causing a circulation of air through said passageways in parallel and through the cylinder.

7. In an internal combustion engine, a cylinder and a piston, said cylinder being provided with a plurality of circumferentially spaced longitudinal passageways in its walls, means associated with said cylinder for displacing by scavenging air the burned gases in the cylinder at the end of the explosion period, and a valved port by which such scavenging air when forced out of said cylinder is conducted through said passageways in parallel.

8. In an internal combustion engine, a cylinder and piston, said cylinder being provided with main intake and exhaust ports which are open during the intake and exhaust periods of the engine and with supplemental exhaust and scavenging-air inlet ports which are opened to sweep out by scavenging air the burned gases in the cylinder at the end of the explosion period, said cylinder walls being provided with a plurality of circumferentially spaced longitudinal passageways which are connected with the main exhaust port when it is open so that the gases discharged from the cylinder during the exhaust period are forced through such passageways in parallel.

9. In an internal combustion engine, a cylinder and piston, said cylinder being provided with main intake and exhaust ports which are open during the intake and exhaust periods of the engine and with supplemental exhaust and scavenging-air inlet ports which are opened to sweep out by scavenging air the burned gases in the cylinder at the end of the explosion period, said cylinder being provided with longitudinal external grooves, and a metal jacket fitting over said cylinder and making longitudinal passageways of said external grooves, and said passageways being provided with connections to the main exhaust port so that when said main exhaust port is open the gases expelled from the cylinder are forced through said passageways.

10. In an internal combustion engine, a cylinder and piston, said cylinder being provided with main intake and exhaust ports which are open during the intake and exhaust periods of the engine and with supplemental exhaust and scavenging-air inlet ports which are opened to sweep out by scavenging air the burned gases in the cylinder at the end of the explosion period, said cylinder being provided with longitudinal external grooves, and a metal jacket fitting over said cylinder and making longitudinal passageways of said external grooves, and said passageways being provided with connections to the main exhaust port so that when said main exhaust port is open the gases expelled from the cylinder are forced

through said passageways, said jacket being of high-heat-conductivity metal and being provided with external heat-radiating flanges.

11. In an internal combustion engine, a cylinder and piston, said cylinder being provided with main intake and exhaust ports which are open during the intake and exhaust periods of the engine and with supplemental exhaust and scavenging-air inlet ports which are opened to sweep out by scavenging air the burned gases in the cylinder at the end of the explosion period, said cylinder being provided with longitudinal external grooves, and a metal jacket fitting over said cylinder and making longitudinal passageways of said external grooves, and said passageways being provided with connections to the main exhaust port so that when said main exhaust port is open the gases expelled from the cylinder are forced through said passageways, said jacket being of high-heat-conductivity metal.

12. In an internal combustion engine, a cylinder and piston, said cylinder being provided with main intake and exhaust ports which are open during the intake and exhaust periods of the engine and with supplemental exhaust and scavenging-air inlet ports which are opened to sweep out by scavenging air the burned gases in the cylinder at the end of the explosion period, said cylinder being provided with longitudinal external grooves, and a metal jacket fitting over said cylinder and making longitudinal passageways of said external grooves, and said passageways being provided with connections to the main exhaust port so that when said main exhaust port is open the gases expelled from the cylinder are forced through said passageways, said jacket being provided with external heat-radiating flanges.

13. In an internal combustion engine, a cylinder and piston, said cylinder being provided with main intake and exhaust ports which are open during the intake and exhaust periods of the engine and with supplemental exhaust and scavenging-air inlet ports which are opened to sweep out by scavenging air the burned gases in the cylinder at the end of the explosion period, said cylinder walls being provided with a plurality of circumferentially spaced longitudinal passageways which are connected with the main exhaust port when it is open so that the gases discharged from the cylinder during the exhaust period are forced through such passageways in parallel, said supplemental exhaust and scavenging-air inlet ports being located in the cylinder walls so that they are covered and uncovered by the piston movement and are uncovered at the end of the explosion period.

14. In an internal combustion engine, a

cylinder and piston, said cylinder being provided with main intake and exhaust ports which are open during the intake and exhaust periods of the engine and with supplemental exhaust and scavenging-air inlet ports which are opened to sweep out by scavenging air the burned gases in the cylinder at the end of the explosion period, said cylinder being provided with longitudinal external grooves, and a metal jacket fitting over said cylinder and making longitudinal passageways of said external grooves, and said passageways being provided with connections to the main exhaust port so that when said main exhaust port is open the gases expelled from the cylinder are forced through said passageways, said supplemental exhaust and scavenging-air inlet ports being located in the cylinder walls

so that they are covered and uncovered by the piston movement and are uncovered at the end of the explosion period.

15. In an internal combustion engine, a cylinder and a piston, said cylinder being provided with a plurality of spaced passageways in its walls, and means associated with said cylinder for displacing by scavenging air the burned gases in the cylinder at the end of the explosion period, said passageways being so connected with the cylinder 30 that when scavenging air is forced out of the cylinder it passes through such passageways in parallel.

In witness whereof I have hereunto set my hand at New Orleans, Louisiana, this first 35 day of August, A. D. one thousand nine hundred and nineteen.

ALFRED CHARLES SINCLAIR.
